US00D435652S

United States Patent [19]

Nazarifar et al.

[11] Patent Number: Des. 435,652

[45] Date of Patent: ** Dec. 26, 2000

[54] SHIELDED FEMALE CONNECTOR

[75] Inventors: **Nader Nazarifar**, Laguna Niguel;
Richard A. Rossback, Irvine; **Gary P. Sorensen**, Lake Forest, all of Calif.

[73] Assignee: **Alcon Laboratories, Inc.**

[**] Term: 14 Years

[21] Appl. No.: 29/102,713

[22] Filed: Mar. 30, 1999

[51] LOC (7) Cl. 24-02

[52] U.S. Cl. D24/129; D23/262

CLAIM

The ornamental design for a shielded female connector, as shown and described.

DESCRIPTION

FIG. 1 is an upper, left, rear perspective view of a first embodiment of the shielded female connector of the present invention.

FIG. 2 is an upper, left, front perspective view of a first embodiment of the shielded female connector of the present invention.

FIG. 3 is an upper plan view of a first embodiment of the shielded female connector of the present invention.

FIG. 4 is a front elevational view of a first embodiment of the shielded female connector of the present invention.

FIG. 5 is a left elevational view of a first embodiment of the shielded female connector of the present invention.

FIG. 6 is a rear elevational view of a first embodiment of the shielded female connector of the present invention.

FIG. 7 is an upper, left, rear perspective view of a second embodiment of the shielded female connector of the present invention.

FIG. 8 is an upper, right, front perspective view of a second embodiment of the shielded female connector of the present invention.

FIG. 9 is an upper plan view of a second embodiment of the shielded female connector of the present invention.

FIG. 10 is a front elevational view of a second embodiment of the shielded female connector of the present invention.

FIG. 11 is a left elevational view of a second embodiment of the shielded female connector of the present invention; and, FIG. 12 is a rear elevational view of a second embodiment of the shielded female connector of the present invention.

The connector of the present invention is used as a fluid connector during microsurgery, particularly ophthalmic surgery, to connect irrigation and aspiration tubings between a surgical handpiece and a control console.
